(57) **CLAIM**

The ornamental design for a cartridge for immunochromatographic test device, as shown and described.

DESCRIPTION

FIG. 1 is a perspective view of bottom, front and left side of a cartridge for immunochromatographic test device showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a cross-sectional view at 8-8 shown in FIG. 2 omitting the internal mechanism.

The portions of the article in broken line are shown for illustrative purposes only and form no part of the claimed design.
